Primary Examiner — Cathron Brooks*Assistant Examiner* — Deanna Fluegeman(74) *Attorney, Agent, or Firm* — Ostrager Chong Flaherty & Broitman P.C.**CLAIM**

The ornamental design for a painting multi-tool, as shown and described.

DESCRIPTION

FIG. 1 is a left side view of the design of FIG. 1;
FIG. 2 is a back view of the design of FIG. 1;
FIG. 3 is a right side elevational view of the design of FIG. 1;
FIG. 4 is a front view of the design of FIG. 1;
FIG. 5 is a front perspective view of the design FIG. 1;
FIG. 6 is a back perspective view of the design FIG. 1;
FIG. 7 is a top view of the design FIG. 1; and,
FIG. 8 is a bottom view of the design of FIG. 1.
The broken lines in the drawings illustrate unclaimed portions of the painting multi-tool and form no part of the claimed design.
